(57) **CLAIM**

The ornamental design for an electrical terminal, as shown and described.

DESCRIPTION

The present application is related by subject matter to a design patent application entitled "Electrical Terminal" and filed on even date herewith under 29/369,333.

FIG. 1 is a top, right, front perspective view of an electrical terminal according to our design;

FIG. 2 is a bottom, left, rear perspective view thereof;

FIG. 3 is a front elevation view thereof;

FIG. 4 is a left side elevation view thereof; and

FIG. 5 is a rear elevation view thereof.

FIG. 6 is a right side elevation view thereof;

FIG. 7 is a top plan view thereof; and,

FIG. 8 is a bottom plan view thereof.

In a preferred embodiment, the nature of this product is an electrical terminal configured for electrically connecting to an electrical devices.

The broken line portion of the figure drawings is included to show unclaimed subject matter only and forms no part of the claimed design.
